COMBINED EXTENSION CORD AND SAFETY SOCKET THEREFOR

Howard Perry Michener, 44 Plainfield Road,
Stirling, N.J. 07980

Filed Mar. 21, 1972, Ser. No. 236,801

Term of patent 14 years

Int. Cl. D13—03

U.S. Cl. D26—1 B

FIG. 1

FIG. 2

FIG. 3

FIG. 4

FIG. 5

FIG. 6

FIG. 7

FIG. 1 is a perspective view of a combined extension cord and safety socket therefor showing my new design with the cord broken away in part to indicate indeterminate length.

FIG. 2 is a front view thereof.

FIG. 3 is a side view thereof.

FIG. 4 is a sectional view taken in the direction of arrows 4-4 of FIG. 3.

FIG. 5 is a rear view thereof.

FIG. 6 is a top plan view of a modified form of the design shown in FIG. 1 wherein dual sockets are disclosed.

FIG. 7 is a cross sectional view of the socket portion shown in FIG. 6.

I claim:

The ornamental design for a combined extension cord and safety socket therefor, as shown.
